(57) **CLAIM**

The ornamental design for a control panel for oven, as shown and described.

DESCRIPTION

FIG. 1 is the front/right-side/top perspective view of a control panel for oven according to our new design;

FIG. 2 is the front elevational view thereof; and,

FIG. 3 the enlargement view of the claimed part of FIG. 1 without dashed line.

The broken lines shown in the drawings represent unclaimed portions of oven.

1 Claim, 3 Drawing Sheets

FIG. 1

FIG. 2**FIG. 3**
